GARMENT

Irving Gerstman, Buffalo, N. Y.

Application March 20, 1935, Serial No. 11,941

2 Claims. (Cl. 2—228)

This invention relates to a garment and is more particularly intended for use in connection with the outer garments of children where it is desirable to have snug fitting cuffs around the ankles and wrists of the child and at the same time to render such cuffs easily removable without requiring removing the child's shoes, although the features of the invention can obviously be employed in connection with other garments.

10 The principal object of the present invention is to provide a garment which has a so-called wind-proof cuff made of an elastic material, such as knitted wool which snugly fits around the user and at the same time can be quickly opened up 15 so as to permit the garment being taken off or put on without the necessity of removing the shoes or gloves of the wearer.

Another object of the present invention is to provide such a cuff construction which can be fabricated at low cost and in which, in particular, the operation of sewing the cuff fastener is reduced by forming the cuff of two pieces so that the fastener can be quickly sewed in place and thereafter the sewing of the garment sections 25 and cuff sections together completed.

In the accompanying drawing:

Fig. 1 is a front elevation of the pants of a child's snow suit showing my invention incorporated therein.

30 Fig. 2 is a vertical section taken on line 2—2 of Fig. 1.

Fig. 3 is a perspective view of the trouser bottom of the garment illustrated in Figs. 1 and 2 and showing the manner in which the knitted cuff is divided into two sections so as to facilitate sewing of the fastener.

Fig. 4 is a view similar to Fig. 3 showing the form of the trouser bottom during the operation of sewing the fastener in position.

40 Fig. 5 is a fragmentary rear elevation of the garment illustrated in Fig. 1.

Fig. 6 is a fragmentary view similar to Fig. 2 showing the manner in which the knee pad of the garment can be reversed as a hole is worn 45 therein.

The snow suit pants shown in the drawing consists of two rear sections 10 and 11 which form the rear parts of the legs of the garment and extend from the cuff to the waist band and 50 are joined together by a seam, as indicated at 12. The front of the garment consists of two upper sections 13 and 14 and two lower sections 15 and 16. The upper sections are joined together by a seam, as indicated at 17, and the upper and lower sections at each side of the garment overlap, as indicated at 18, the overlapping portions being sewed together by stitching, as indicated at 19 and 20. The corresponding outer edges of the sections 10, 14 and 16 are joined together by an 55 outside seam 21 and similarly the outside edges

of the sections 11, 13 and 15 are joined together by an outside seam 22. The corresponding side edges of all the sections are joined together by a seam 23 which extends along the crotch of the garment and down to the cuffs. The sections 5 10, 11, 13, 14, 15 and 16 so joined are preferably made of a sturdy and relatively inelastic material such as woven wool, the weaving being such as to provide a firm and closely woven fabric which is relatively unstretchable, as compared 10 with the knitted material of which the cuffs are made as hereinafter described.

The cuffs or bottoms of the pant legs are each made of two sections 25 and 26 which are composed of knitted wool or the like and are 15 elastic so that when applied the cuff tightly embraces the child's ankle and provides a snow and weather-proof cuff which protects the child's ankles against snow and cold and at the same time permits it to indulge in rough and tumble 20 sports. The cuff section 25 forms a continuation of the lower rear section of the pant leg to which it is attached and is joined to this lower rear section by stitching 27. Similarly the companion cuff section 26 forms a continuation of the 25 lower front section of the corresponding leg of the garment and is joined to this section by a line of stitching 28. The side seams 21 and 22 of the garment are not continued down to the cuffs but are stopped adjacent the lower part of the 30 knee pads so as to provide a slit 29 in which a non-separating fastener of the zipper or Talon type is sewed. Such fasteners each consist of strips of cloth 30 and 31 having sewed in their opposing margins a plurality of metal hooks 32 35 which are engaged so as to lock the two sets of hooks together by a traveling shoe 33 through which the hooks pass on sliding the shoe from one end of the two rows of hooks to the other.

The fastener thus described is applied to the 40 corresponding pant leg while the pant leg is flat as illustrated in Fig. 4. The fastener is placed in the position there shown and is sewed to the two cuff sections 25 and 26 and to the corresponding pant leg sections by stitching 34. After 45 the fastener is so applied so as to form a quickly releasable closure for the slit 29 the garment is completed by sewing the crotch seam 23, this stitching joining the inwardly facing margins of the two cuffs of the garment and also the 50 corresponding inner edges of the sections 10, 11, 13, 14, 15 and 16.

It will be seen that by the provision of a Talon fastener in a slit extending through the pant legs of the garment and also through the elastic cuff 55 thereof, the advantage of the elastic cuff in protecting the child's ankles against weather and snow is obtained and at the same time the cuff and pant legs are readily opened up so as to permit the pants being taken off without removing the 60

child's shoes. At the same time it will be noted that the body of the pants is made of a relatively inelastic, closely woven material which will withstand hard usage and stay in shape. It will further be noted that by making each cuff in two sections the Talon fastener can be readily sewn in while the garment is in the flat, as illustrated in Fig. 4, whereas this operation would be extremely difficult if the cuff were made of one piece and the seam 23 sewed before the Talon fastener secured. Moreover, when it is attempted to sew the Talon fastener after the rest of the garment is complete it is impossible to do so without stretching the material and this is liable to result in unevenness in the finished product.

As briefly explained the front sections forming the two legs of the pants overlap as indicated at 18 so as to provide a knee pad of double thickness of material. It will be seen that this construction permits the garment to be readily repaired when the child wears a hole in the knee pad. For example, should the child wear a hole in the lower part of the knee pad 18 the stitching 19 can be ripped out and the upper part of the lower pant leg section folded down, as illustrated by dotted lines in Fig. 2, so as to cover the hole whereupon this part can be re-sewed in such position. If the child should wear another hole in this folded down part or if a neater job should be desired, the sections forming the pad 18 can be reversed, as illustrated in Fig. 6, so that the outer part which is worn through is disposed inside of the other part of the knee pad. This is accomplished, of course, by ripping the stitching 19 and 20 and reversing the lap. In Fig. 6 is illustrated, in dotted lines, another patch that can be made by ripping the stitching along the lower edge of the knee pad 40 and folding up this section and re-sewing it.

To the upper ends of each of the back sections 10 and 11 are secured waist band sections 40 and 41 of the same material, these being joined by stitching 42. The waist band sections 40 and 41 are stitched together as indicated at 43, the seam formed by the stitching 43 forming a continuation of the seam 12 so that if the garment is required to be taken in around the waist the seam 43 and the upper end of the seam 12 can be ripped and re-sewn. The waist band sections 40 and 41 are made of a double thickness of the same material which forms the body of the pants so as to form a relatively stiff band which adequately supports the back of the garment and at the same time fits the wearer snugly. The side seam 21 of the garment is not continued up to the waist band but is stopped short so as to provide a slit 44 in which a quick detachable Talon or zipper fastener 45 is secured, one side 60 of the fastener being secured to the waist band section 40 and to the corresponding edge of the section 10 along the slit 44 and the other side being stitched to the section 14 and at its upper end being secured to a small section 46 of the 65 waist band which is made in the same manner as the sections 40 and 41. However, that section of the waist band between the sections 41 and 46 is made of an elastic material 47 and is preferably made of knitted wool which is stretchable and also elastic so as to resume its initial 70 shape and is also soft so that the section 47

does not interfere with the free bending movements of the wearer. This stretchable section 47 is stitched, while stretched, to the upper edge of the front body sections 13 and 14, as indicated at 48 and is suitably stitched to the vertical opposing edges of the stiff waist band sections 40 and 46. It is apparent that by reason of the elasticity of this front waist band section the relatively stiff rear waist band sections 40 and 41 are drawn snugly against the small of the back of the user. Furthermore, the elasticity of the front section 47 supports the garment on the hips of the wearer even though the zipper is not drawn up to its full extent. This permits of convenience in putting on the garment especially when a shirt is to be tucked in.

From the foregoing it is apparent that the present invention provides a very simple and inexpensive garment which provides snug fitting, weather-proof elastic cuffs on a garment of closely woven material, and at the same time permits these cuffs to be quickly opened up so as to remove the garment over shoes or the like. Furthermore, the cuffs are so constructed that the Talon or zipper fastener can be quickly applied in fabricating the garment.

I claim as my invention:

1. A garment including portions adapted to embrace the limbs of the wearer, each of said portions being made of two sections of relatively inelastic and closely woven material, a cuff composed of two pieces of relatively elastic material secured to the extremity of said portion, a line of stitching uniting the corresponding edges of said sections and extending from the outer edge of said cuff to the opposite edges of said sections of closely woven material, and the edges of said sections of closely woven material on the side opposite said line of stitching being united by a seam extending to a point spaced from said cuff so as to leave a slit extending through the cuff and into said closely woven material and a quickly releasable fastener securing the edges of said slit together substantially the full length thereof so as to provide an elastic cuff which tightly embraces the limb of the wearer.

2. A garment including portions adapted to embrace the limbs of the wearer, each of said portions being made of two sections of relatively inelastic and closely woven material, a cuff composed of two pieces of relatively elastic material secured to the extremity of said portion, a line of stitching uniting the corresponding edges of said sections and extending from the edge of said cuff to the opposite edges of said sections of closely woven material, and the edges of said sections of closely woven material on the side opposite said line of stitching being united by a seam extending to a point spaced from said cuff so as to leave a slit extending through the cuff and into said closely woven material and a quickly releasable fastener of the Talon non-separating type securing the edges of said slit together substantially the full length thereof so as to provide an elastic cuff which tightly embraces the limb of the wearer and at the same time renders the garment quickly removable without having to remove the wearer's shoes or gloves.

IRVING GERSTMAN.
